CLAIM

The ornamental designs of a wave bracket and eclipse seat, as shown and described.

DESCRIPTION

FIG. 1 is a top, front, left side perspective view of a wave bracket and eclipse seat of the new design, the broken lines forming no part of the claimed design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a top, front, left side perspective view of a first alternative embodiment of a wave bracket and eclipse seat of the new design, the broken lines forming no part of the claimed design.

FIG. 9 is a top, front, left side perspective view of a second alternative embodiment of a wave bracket of the new design, the broken lines forming no part of the claimed design.

FIG. 10 is a front elevation view thereof.

FIG. 11 is a rear elevation view thereof.

FIG. 12 is a left side elevation view thereof.

FIG. 13 is a right side elevation view thereof.

FIG. 14 is a top plan view thereof; and,

FIG. 15 is a bottom plan view thereof.
